(57) **CLAIM**

The ornamental design for mobile device dock, as shown and described.

DESCRIPTION

FIG. 1 is a perspective view of a the mobile device dock showing the new design;

FIG. 2 is a front elevation view thereof;

FIG. 3 is a rear elevation view thereof;

FIG. 4 is a right elevation view thereof;

FIG. 5 is a left elevation view thereof;

FIG. 6 is a top plan view thereof;

FIG. 7 is a bottom plan view thereof;

FIG. 8 is a rear elevation view thereof wherein a cap member is spaced therefrom;

FIG. 9 is a perspective view thereof wherein a positioning grip is spaced therefrom;

FIG. 10 is a front elevation view thereof interconnected to a mobile device and a positioning grip;

FIG. 11 is a rear elevation view thereof interconnected to a mobile device and a positioning grip;

FIG. 12 is a right elevation view thereof interconnected to a mobile device and a positioning grip;

FIG. 13 is a left elevation view thereof interconnected to a mobile device and a positioning grip;

FIG. 14 is a top plan view thereof interconnected to a mobile device and a positioning grip; and,

FIG. 15 is a bottom plan view thereof interconnected to a mobile device and a positioning grip.

The broken lines are for the purpose of illustrating environment and forms no part of the claimed design.
